UNITED STATES PATENT OFFICE.

AUGUST G. FISCHER, OF PHILADELPHIA, PENNSYLVANIA.

WAGON-SPRING BUFFER.

SPECIFICATION forming part of Letters Patent No. 430,770, dated June 24, 1890.

Application filed October 30, 1889. Serial No. 328,681. (No model.)

To all whom it may concern:

Be it known that I, AUGUST G. FISCHER, a citizen of the United States, residing at Philadelphia, in the county of Philadelphia and 5 State of Pennsylvania, have invented certain new and useful Improvements in Wagon-Spring Buffers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to buffers, and has for its object the provision of a buffer attached to wagon-springs to prevent the tail-board from striking the spring-head when the tail-board is released and swung down.

20 The invention consists in a spring-head provided with a buffer, of rubber or other elastic material, which projects beyond the head of the spring and receives the stroke or concussion of the tail gate or board when the

25 latter is swung down.

The simplest form of embodying the invention consists in forming a hole through the face of the spring-head and passing a rubber buffer having an enlarged butt through said opening from the inside before the head is fixed upon the spring. Such form of embodiment is shown in the accompanying drawings, wherein—

Figure 1 is a side elevation of the rear end 35 of a wagon, showing the buffer applied to a spring. Fig. 2 is a side elevation of the end of the spring on an enlarged scale, showing the buffer. Fig. 3 is a plan view of Fig. 2. Fig. 4 is a plan view of the head and buffer 40 removed from the spring. Fig. 5 is an end elevation of the head, and Fig. 6 is a longitudinal section of Fig. 4.

Similar letters of reference indicate corresponding parts in all the figures where they 45 occur.

A A are the leaves of the springs.

B is the head of the spring, applied in the usual way, and C is the buffer. The head B

is provided with a tapering hole b, and its face may be carried out into the sides b' b', 50 thus giving a long firm grip upon the buffer C, which, as shown, has a tapered butt c', and is passed through the opening b from the inside of the head before the head is set in place. The end of the spring abuts against 55 the inner end of the buffer and holds it in place, while the outer end of the buffer projects beyond the face of the spring-head and receives the tail-board when it swings down, as shown in Fig. 1. It is evident that the 60 buffer may be applied to the end of the spring in different ways; but that shown in the drawings I believe to be the best.

Instead of having the buffer set in the head of the spring, it may be held in a detachable 65 piece, which can be clamped or otherwise secured to the spring, so that the buffer can be manufactured and sold separate from the spring.

Having thus described my invention, what 70 I claim, and desire to secure by Letters Patent, is—

1. A vehicle-spring having a head covering one end of the long leaves, said head being provided with an opening in which a buffer 75 is secured in such a position that it projects beyond the outer end of the spring, substantially as set forth.

2. A vehicle-spring having a head covering one end of the long leaves, provided with an 80 opening through the end thereof, and a buffer passed through said opening from the interior and abutted against the end of the leaves, as set forth.

3. A vehicle-spring having a head covering 85 one end of the long leaves and provided with the extended sides b' b' and tapering opening b, in combination with a buffer C, having a tapering butt c', substantially as and for the purpose set forth.

In testimony whereof I affix my signature in presence of two witnesses.

AUGUST G. FISCHER.
